METHOD FOR HUMIDIFYING BOARDS OF
WOOD FIBRE OR SIMILAR MATERIAL

Bengt-Åke Larsson, Farsta, Sweden, assignor to Aktiebolaget Svenska Flaktfabriken, Stockholm, Sweden

1 Claim. (Cl. 34—13.8)

The present invention relates to a method which, in the humidifying of boards of wood fibre or similar material by means of moist air, will ensure a uniform distribution of moisture in the boards.

Humidifying of fibrous material, for example sheets of wallboard and similar material, has hitherto been carried out with moist air in streams parallel to the material. Moist air has been passed across the material in some cases and along the material in other cases. In both cases a substantial drop in the relative humidity of the air used for humidifying will occur in the direction of air flow, which will cause a difference in the humidity of the board on supply and exhaust sides. In other words, the moisture absorption of the board will travel forward like a wave, and a relatively long time must be allowed before the board has attained an approximately uniform moisture ratio throughout.

This difference arising in the humidity of the air is the cause of other disadvantages, especially as regard swelling, bulging, alteration in thickness etc., which are associated with an uneven supply of moisture.

The transmission coefficient of diffusion is of great importance in the humidifying of material. An analogy exists between the transmission coefficient of diffusion and the heat transmission coefficient α , usually expressed by Lewis' law

$$\beta = k \cdot \frac{\alpha}{\gamma \cdot c_p}$$

where γ = density of the air and c_p the specific heat. The constant k is dependent on the kind of flow and the state of the air. In other words it can be said that a high value of α will be accompanied by a high β value. Under certain conditions, it can therefore be said that the higher the value of α (value of β), the shorter will be the time required to impart a certain desired moisture ratio, for example to a wallboard.

The object of the invention is to eliminate the said disadvantages and to permit a considerable reduction in the treatment time and to ensure a uniform moisture distribution in the finished boards.

The invention is characterized in that the moist air is supplied in a saturated or practically saturated state and in the form of evenly spaced jets with a high velocity and is blown against the boards at right angles against both sides.

Humidifying of wood fibre boards involves a swelling. It is a fact that this swelling is greatest during the beginning of humidifying; it is intensive up to a moisture ratio of 3 to 4%, and subsequently proceeds relatively slowly. An intensive humidifying causes an erection of the fibres in the outer layer of the board, depending on stresses arising there due to the said swelling. When humidifying in air at 60 to 65° C., the erection of fibres is very small or does not take place at all; at higher temperatures, for example 90° C., it is violent. The time taken to humidify a board to a certain percentage is approximately twice as long at 60° C. than it is at 90° C.

In order to reduce the humidifying time and simultaneously avoid erection of the fibres, according to a practical embodiment of the method, the procedure can be such that the humidifying takes place in at least two

stages, separated by an interval, the temperature during the first stage being maintained at approximately 60–65° C. and the temperature in the final stage at approximately 80–85° C.

5 The invention will be described in more detail with reference to the accompanying drawing wherein:

FIG. 1 is a diagram illustrating the method of humidifying in accordance with the present invention;

10 FIG. 2 is a fragmentary side view of a humidifying apparatus in accordance with the present invention;

FIG. 3 is a sectional view taken on the line 3—3 of FIG. 2; and

15 FIG. 4 is a thumbnail sketch in side elevation of apparatus for continuously humidifying in accordance with the present invention.

The method of the invention is illustrated in the accompanying diagram, FIG. 1. The diagram shows the approximate relationship between moisture ratio (u) and time (tid) taken for a humidifying process according to

20 the invention. During the time O—A the board is subjected to fairly moderate air conditions with regard to the erection of fibres, for example, air at a temperature of 60° C. and a relative humidity of 85%. The board is humidified here to 3 to 4%.

25 During the humidifying of the board, heat will be generated, partly due to condensation in the fibres, partly because the heat of swelling is released. The simplest way of removing this heat is by ventilation of the apparatus being used. In the diagram this has been indicated by the interval of time A—B. During the following interval B—C the board is humidified at a higher temperature until the desired humidity is reached for example, by air at a temperature of 80° C. and a relative humidity of 90%.

30 During the interval A—B, ventilation can be combined with a cooling of the board, which helps to reduce the time B—C.

35 Humidifying according to the invention can be carried out either continuously or in batches.

A continuous apparatus for carrying out the method is presupposed to consist of a treatment channel provided with elements for the transport of the boards and equipped with elements for humidifying and circulation of the treatment medium. The apparatus is characterized in that on both sides of each transport plane there are air distribution boxes, the walls of which facing the transport plane are provided with a large number of equally spaced discharge openings for blowing on treatment medium in the form of jets directed substantially at right angles to the boards, and that the treatment channel is divided up by means of partitions into two or more effective treatment zones with intermediate equalizing zones, the latter being provided with outlets for exhausting ventilation air for the purpose of removing of excess heat generated in the channel.

40 Thus the invention is based on the realization that the conditions essential for obtaining a uniform distribution of moisture are that the treatment medium be supplied uniformly distributed and in such a manner that a high heat transmission coefficient and transmission coefficient of diffusion are attained. According to the invention, this is achieved by utilization of moist air in a substantially saturated state blown perpendicularly against both sides of the board.

45 In addition to the advantage of a first-class finished product—with an absolutely uniform moisture ratio—gains are made in that initial costs are considerably reduced and the need for extra space for moisture equalization after humidifying is eliminated and in that the boards can proceed for further treatment without delay.

50 An apparatus for carrying the invention into practice will now be described with reference to FIGS. 2 to 4 inclusive. In the figures, 1 designates a foundation on which

the section 2 of a continuously-operating humidifying apparatus is supported. 3 designates circulating fans driven by means of motors 4 and belt drives. The circulating fans 3 are arranged in pairs on opposite sides in order to obtain a uniform air distribution in the apparatus. A series of humidifying chambers 5 are arranged in the foundation 1, suitably one for each section. These are provided, in a conventional manner, with banks of nozzles 6, drain gratings 7, a float valve 8 for supply of make-up water, a drain 9 for recirculating water, and a overflow 10. A number of blower boxes 11 are located in the sections situated above the foundation. The horizontal walls of these boxes could be perforated or provided with slots for right-angle discharge of air. Conveyors 12 are arranged between the blower boxes. The boards to be humidified 13 are transported on these conveyors. The conveyors can possibly be fitted with double rollers to prevent lateral movement of the boards during transport. Air introduced into the boxes 11 through openings 14 in the right hand side of the apparatus is forced out through perforations 15 on to the boards, to which it gives up moisture. The air is then passed sideways out to the left hand side of the apparatus and is blown by fan 3 through the humidifying chamber, where it is again humidified. Since the apparatus is divided up into a number of sections and the quantity of circulating air is very large, the alteration in the relative humidity of the air will be very small, both in the lengthwise direction of the apparatus and crosswise, which provides a uniform distribution of moisture throughout the entire board, and to a great extent helps to shorten the time required for humidifying. As shown in FIG. 4, the apparatus is divided into a first treatment zone 21, a second treatment zone 22, and an intermediate equalizing zone 23, all separated by partitions. The equalizing zone 23 is provided with an outlet 24 for exhausting ventilating air to remove excess heat generated in the previous treatment zone 21.

The condition of the air in the respective zones and humidifying chambers is controlled by conventional temperature control devices (not shown), for example, heat exchangers of the type disclosed in prior Patent Number 2,920,398; 2,939,222; or 3,070,902. The passage of the heated air through the humidifying chambers insures substantial saturation of the air flowing therethrough.

What I claim is:

A method of humidifying boards of wood fibre or similar material which are subject to swelling at the start of humidification and erection of the fibres in the outer layer of the boards, wherein moist air is blown at right angles against both sides of the board at high velocity and in the form of evenly spaced jets, the improvement wherein erection of the fibres is avoided by humidifying the boards in at least two stages with heated air which is in a substantially saturated state, and the stages are separated by a period of rest in which the boards are ventilated and cooled to remove the heat generated during humidification of the boards in the first stage due to condensation in the fibre and the heat of swelling, the temperature in the first stage being maintained at approximately 60-65° C., and the temperature in the final stage being maintained at approximately 80-85° C.
